UNITED STATES PATENT OFFICE.

GEORGE H. WOODWARD, OF SAN FRANCISCO, CALIFORNIA.

EXTERNAL VALVE-CHAMBER.

No. 878,924.

Specification of Letters Patent.

Patented Feb. 11, 1908.

Application filed January 11, 1907. Serial No. 351,895.

To all whom it may concern:

Be it known that I, GEORGE H. WOODWARD, a citizen of the United States, residing at San Francisco, in the county of San Francisco and State of California, have invented new and useful Improvements in External Valve-Chambers, of which the following is a specification.

My invention relates to gas engines, but more particularly to the admission port, which is so constructed that its position relative to that of the exhaust may be varied at will and to a valve for controlling the quantity of charge, and to vary position of said admission port; and also to the construction of the piston in which a passage is provided so as to admit the charge upward through its center and the exhaust ports and passages for the burned gases. The object of this construction is to provide a means by which the volume of charge may be under perfect control, and also by the same means to regulate the time of admission of the charge. The object of the passage through the piston terminating at its center is to force the fresh charge upward throughout the center of the cylinder. To take the place of the burned gas which escapes through the exhaust ports located in the wall of the cylinder in a position so as to be entirely uncovered by the piston, when it is in its lowest position and distributed on the circumference. This allowing the burned gases to pass out freely at all points around the incoming charge. An annular passage of ample capacity is provided in this construction through which the gases pass from the exhaust port on either side to the final exhaust pipe connected with the cylinder in the usual manner.

In the embodiment of my invention shown in the accompanying drawing:—Figure 1 is a central section of a two cycle gas engine with my valve in connection therewith and shown as open to its fullest extent. Fig. 2 is an enlarged vertical section of the valve, the inlet ports and parts in proximity. Fig. 3 is a front elevation showing the rows of inlet or admission ports, and the valve in the position of partly covering said rows. Fig. 4 is a horizontal section of the cylinder in the level of the admission ports showing the valve in top plan view.

The gas engine shown is of a well known type and its construction and operation require no extended description. On its first upward stroke the piston 1, uncovers the

ports 2, which open into the cylinder from the casing 3 as shown in Fig. 3 the casing being connected to the carbureter by a pipe 4, and a charge of gas is drawn into the crank case. On the next down stroke the piston compresses the charge in the crank case and at the extremity of said stroke the piston forces this charge out through the rows of ports 5 and into the valve casing 6 which projects from the side of the cylinder, and with which the said ports 5 connect as shown in Fig. 1. The valve casing 6 forms the means of communication from the crank case and cylinder below the piston to the compression and combustion space in the cylinder above the piston. The piston is provided with a passage 7 which first extends horizontally inwardly, and is then turned vertically, as best shown in Fig. 1, and which delivers the fresh charge into the cylinder above the piston upwardly and centrally, whereby such fresh charge spreads in all directions equally, while the piston is at its lowest point. At such point, the exhaust ports 8, Figs. 1 and 3, opening from the cylinder into the surrounding casing 3, which is not shown in Fig. 1, but is shown in Fig. 3, are open and the burned charge is driven out. The exhaust pipe 9, communicating with the casing 3 is shown in Fig. 3.

Of course a suitable igniter is provided at the upper end of the cylinder, which I have not considered it necessary to show, as it forms no part of the invention, and may be of any type or kind, many of which are well known to those skilled in the art.

To an engine operating generally in the manner described, my variable admission valve is applied, and is constructed and arranged to operate in connection with such an engine in the following manner.

Referring more particularly to Figs. 3 and 4 it will be seen that on one side of the cylinder, and forming the inner boundary of the valve casing 6 is a plane flat surface provided with horizontally disposed rows of perforations 11 leading directly into the passage 7. Three of such rows are shown in the present case, and the valve chamber extends above and below them. The admission valve is a plate 12 having an inner flat plane face adapted to slide upon the plane perforated surface just described in curvilinear wall of the casing 6. A valve rod 14 is secured to this lug, which passes down through suitable guides, as 15, in the valve casing,

and below and outside of said casing, is connected to a vertically movable rod 16. This rod forms one of a series of connections from the valve to the governor of the motor as shown in Fig. 1, the other connections being the pivoted lever 17, the double grooved sliding sleeve 18 on the motor shaft and the governor levers 19.

With the motor throttled down and running idle or under a light load, the gas is admitted to the combustion chamber much later than in the event of the motor running faster or under a full load, because the variable admission valve is almost closed, allowing burned gases in combustion chamber more time in which to be exhausted from said chamber.

In the event of the motor running faster or under full load, the valve 14 would be wholly or nearly wide open, so that the incoming charge of gas has the full scavenging effect to expel the burned gases and clear out the combustion chamber.

The motor can be throttled and the valve controlled by hand instead of automatic regulation, as by a suitable lever connected to such valve instead of the valve being connected to the governor for automatic regulation.

30 What I claim is:

1. A gas engine of the two cycle type comprising a cylinder, a piston therein, said piston having a central opening in its upper end and a passage leading from one side near the top to said opening, an external valve chamber secured to the cylinder, the cylinder wall having ports connecting said valve chamber with the said passage, when the piston is at

or near the end of its outward or working stroke a valve in said valve chamber controlling said ports, a governor, means for actuating the valve from the governor, the cylinder wall and said piston having ports connecting said valve chamber with the interior of the cylinder below the piston when said piston is at or near the limit of its working stroke, said cylinder wall having on the side opposite said valve chamber an inlet port below the piston adapted to be uncovered by the piston at or near the limit of its compression stroke and an exhaust port adapted to be uncovered by the piston at or near the limit of its working stroke.

2. In a gas engine of the two cycle type, the combination with the inlet port to the combustion space for supplying the combustible mixture, of a valve coöperating with said port and normally located above the same, and means for moving said valve downwardly to close the upper part of said port as the speed of the engine increases, substantially as described.

3. A two cycle engine having a fuel inlet port comprising a plurality of perforations and a slide valve normally located above said port and means for moving said valve downwardly, whereby the upper perforations may be closed first, substantially as described.

In testimony whereof I affix my signature in presence of two witnesses, this twenty- 70 third day of November 1906.

GEORGE H. WOODWARD.
